[57] CLAIM

The ornamental design for a folding table, as shown and described.

DESCRIPTION

FIG. 1 is a top plan view of a folding table showing the new design;

FIG. 2 is an end elevation thereof looking from the left of FIG. 3;

FIG. 3 is a front elevation thereof;

FIG. 4 is a bottom plan view thereof;

FIG. 5 is a rear elevation thereof;

FIG. 6 is a top plan view thereof with the table folded;

FIG. 7 is a front elevation thereof with the table folded;

FIG. 8 is an end elevation thereof with the table folded, looking from the right of FIG. 7;

FIG. 9 is a bottom view thereof with the table folded; and, FIG. 10 is a rear elevation thereof with the table folded.

The end elevations looking from the right of FIG. 1 and the left of FIG. 7 are mirror images of FIG. 2 and 8, respectively.
